UNITED STATES PATENT OFFICE.

MERRILL DAVIS, OF DETROIT, MICHIGAN.

INTERNAL-COMBUSTION ENGINE.

1,307,186.

Specification of Letters Patent. Patented June 17, 1919.

Application filed June 5, 1916. Serial No. 101,758.

To all whom it may concern:

Be it known that I, MERRILL DAVIS, a citizen of the United States of America, residing at Detroit, in the county of Wayne and 5 State of Michigan, have invented certain new and useful Improvements in Internal-Combustion Engines, of which the following is a specification, reference being had therein to the accompanying drawings.

10 This invention relates to engine construction and in the particular embodiment of the invention shown in the drawings, I have shown it applied to that class of internal combustion engines, commonly known as the 15 four-cycle or four-stroke, although in its broader aspects the invention is not limited to the particular use mentioned.

Among the objects of the invention are to provide a construction in which the burnt 20 charge is completely displaced or forced out of the cylinder before the admission of another charge into that cylinder; to provide a construction in which the efficiency of the engine is much greater than the engines in 25 which there is no provision for positively expelling all of the burnt gases; to provide a construction in which the valve mechanism that controls the inlet and exhaust to and from the cylinder can be utilized for obtaining 30 the complete scavenging of the burnt gases; to so construct and arrange the parts that there will be sufficient space for the compressed gases just before the explosion stroke, this space, however, being filled by a 35 part of the valve mechanism at the end of the exhaust stroke, and in general to provide a simple and efficient construction of the character above referred to. The invention further resides in such features of construction 40 and arrangements and combinations of parts as will more fully hereinafter appear.

In the drawings:

Figure 1 is a vertical cross sectional view through the cylinder of an engine to which 45 my invention is applied;

Figs. 2, 3, 3^a and 4 are similar fragmentary sectional views showing the parts in different positions of adjustment;

Figs. 5 and 6 are elevational views showing 50 the drive mechanism for the valves.

Describing in detail the construction shown in the drawings, A designates the cylinder and B the piston longitudinally reciprocating within the cylinder. At the 55 upper end the cylinder has a contracted

opening C while the closed end D of the piston has a concaved seat E. The arc of curvature of this seat E corresponds to that of the rotating valve F, and the parts are so arranged that in certain positions of adjustment a portion of the valve fits within the seat E so that, as shown in Fig. 3 there is practically no clearance between the piston head and the portion of the valve which forms the end wall of the cylinder. 60

In the particular construction shown the axis of the valve F extends transversely to the axis of the cylinder and the opposite sides of the valve are recessed to provide concaved portions G and G' located between alternate convex portions H and H'. This valve fits within a valve casing J at one side of which there is an inlet opening K and the other side of which there is an exhaust port L. The valve may be driven from the 70 crank shaft by various mechanisms but in the drawings I have shown a worm gear arrangement in which one half of the gear M is provided with spirally arranged teeth N which graduate into parallel form on the 75 remaining half of the worm. As the engine shown is of the four-cycle type the gears O are of such size that they are driven at half the speed of the crank shaft, during the period in which the valve member is rotating. 80 However the parallel arrangement of the teeth on one side of the driving gear or worm N will hold the valve from rotation 85 part of the time.

The operation of the arrangement above 90 described is as follows: With the parts in position shown in Fig. 1 the piston has just moved upward to the end of the compression stroke and is just starting the power stroke. The chamber formed by the concaved portion G of the valve and the concaved seat E of the piston is filled with compressed gas, which when ignited will force the piston downward until it reaches the position shown in Fig. 2. Here it has reached the 100 end of the power stroke and is just beginning the exhaust stroke. The inclined teeth N of the gear M have at this point begun to rotate the gear O and thus turn the valve F until its concaved portion registers with the exhaust port L. The cylinder is therefore open to exhaust during the time in which the piston is moving from the position shown in Fig. 2 to that shown in Fig. 105 3. It will be noticed that when the piston 110

has reached the end of its exhaust stroke the valve has been rotated to a position in which there is practically no clearance between its convex surface H and the 5 end of the piston. Thus the space is mechanically filled and there is a complete scavenging of all the burnt gases. As the piston starts down on the suction stroke the valve F continues to rotate and communication is opened from the inlet port 10 K to the explosion chamber through the concaved portion G' of the valve. As the piston moves down on the suction stroke it tends to create a vacuum in the explosion 15 chamber which will draw a full charge of gas into the cylinder. Then when the piston has reached the end of its suction stroke and starts upward on the compression stroke, the driving gear N will have been 20 moved to a position in which the parallel portion of the teeth engage with the gear O and thus holds the valve from rotation during the entire compression and power strokes.

25 In order to facilitate the scavenging of the gases, I may in some instances, employ the arrangement shown only in Fig. 1 in which there is a Venturi tube Q located in the exhaust passage R and connected into 30 the upper portion of the valve chamber J. By this arrangement, when the burnt gases rush out through the exhaust passage they will produce a suction on the tube S and tend to create a vacuum in the concaved 35 chamber G so as to draw out any exhaust gases that may remain in this chamber.

Since the loss in efficiency in internal combustion engines, particularly of the four-cycle type, is generally due to inability 40 to completely expel the burnt gases, which dilute and diminish the quantity of the incoming charge, it is obvious that an engine constructed in accordance with my invention is a material advancement in the art.

45 I do not however desire to limit the invention entirely to internal combustion engines,

nor to any of the details of construction except as is specified in the appended claims.

What I claim as my invention is:

1. In an engine, the combination with a cylinder, of a piston reciprocating therein and having a concaved end, a valve member forming a part of the head of said cylinder and having a plurality of convex portions, each adapted in one position of adjustment to closely fit within the concaved end in the piston. 55

2. In an engine, the combination of a cylinder, a piston moving therein, of a valve chamber located at one end of said cylinder, 60 said valve chamber having an inlet and an exhaust passage leading into it from approximately opposite sides, of a valve member disposed therein, said valve member having concave and convex sides disposed 65 so as to be alternately brought into register with said cylinder, of a passage leading from said exhaust passage and terminating in top of said valve chamber at a point where one of the concave sides of said valve 70 member will register therewith at the same time that another of the concave sides of said valve member is disposed inwardly in respect to said cylinder.

3. In an engine, the combination with a cylinder and a piston moving therein, of a rotatable member forming a part of the end of said cylinder, said rotatable member having alternately disposed concave and convex sides, and means for exhausting 80 one of said concave sides while the other is in communication with the cylinder. 75

4. In an engine, the combination with a cylinder and a piston moving therein, of a rotatable valve member forming a part of the end of said cylinder, said rotatable valve member having a plurality of concave portions, and means for exhausting one of said 85 concave portions while the other is in communication with the cylinder. 90

In testimony whereof I affix my signature.
MERRILL DAVIS.
